SPLIT-TRAIL GUN CARRIAGE

Nicolas Emilien Methlin, Paris, France, assignor
to Schneider & Cie., Paris, France, a company
of France

Application April 2, 1934, Serial No. 718,717
In France June 30, 1933

16 Claims. (Cl. 89—40)

This invention relates to an improvement in the construction of field gun carriages provided with split trails, and comprises a device for the resilient suspension, from the set of wheels, of the aggregate comprising the trail legs, the top carriage and the oscillating gun and cradle which is trunnioned in the said top carriage.

In the gun carriage according to the invention that part of the assembly which may be called the lower carriage or "trail system" is constituted, in a manner known per se, by a rocking beam which itself is pivoted to the axle of the set of wheels by a longitudinal pivot disposed perpendicularly to the said axle and to the rocker, the vertical pivot for training the top carriage and the oscillating gun and cradle, which are supported by the said top carriage, being provided on the said rocking beam.

The invention is characterized by providing on the axle and trail legs the complementary members of two resilient supports, the said members cooperating when the trail legs are brought together for the travelling position, and conversely ceasing to be in engagement when the trail legs are spread apart for the battery position. The said complementary members will be preferably constituted by a resilient buffer and a supporting finger, respectively, the buffers being carried by the axle and the supporting fingers by the trail legs, or vice versa. According to the invention, the said device may advantageously be combined with a resilient-bush connection between the axle and the hinge pivot of the trail-carrying rocking beam, a mutual guide being provided in this case, through the medium of the suspension members, between the axle and the trail legs when the latter are in the travelling position.

Various constructional forms of the invention are shown by way of example in the accompanying drawings.

Figure 1 is a plan view of a portion of a gun carriage embodying the invention, showing the trail-carrying rocking beam in which is pivoted the top carriage carrying the oscillating gun and cradle, the trail legs pivoted to the said rocking beam being shown in solid lines spread out for the battery position, in which the resilient suspension is inoperative, and in chain lines brought together for travelling, in the operative position of the suspension means.

Figure 2 is a corresponding sectional elevation along the line II—II of Figure 1, the trail legs being shown in solid lines and in the travelling position only.

Figure 3 is a detail sectional elevation on a larger scale showing the complementary members of the resilient suspension in the travelling position.

Figure 4 is a side elevation on a larger scale showing the end of one of the trail legs carrying

one of the suspension members and locked in the battery position. This figure corresponds to the outline shown in solid lines in Figure 1.

Figure 5 is a detail showing, in cross sectional elevation along the axis of the carriage, of the resilient-bush additional suspension device.

Figures 6 to 9, inclusive, show a modification of the invention in plan (Figures 6 and 7), cross section (Figure 8) and sectional elevation (Figure 9), respectively.

Figures 10 and 11 are plan views similar to Figures 1 and 6 showing two other modifications of the invention.

Figure 12 is a partial plan view corresponding to Figure 11 and showing the members in a different position.

Figure 13 is a sectional elevation showing a modification of the relative arrangement of the complementary members of the suspension, the said members being shown in the travelling position.

Figure 14 is a plan view corresponding to Figure 13 showing the members in the battery position.

The gun carriage according to the invention comprises, in the known manner, a set of wheels on the axle *a* of which a rocking beam *b* is mounted to oscillate about a pivot *b'* disposed in the longitudinal axial plane of the carriage. Pivoted by pins *c'* to the said rocking beam *b* are the so-called "trail legs" *c* which, by being spread apart, may be brought into the position shown in solid lines in Figure 1, for bringing the gun into the battery position, or may be brought into the travelling position by bringing them together into the position shown in chain lines in the same figure.

According to the invention, for travelling, a resilient suspension is provided between the trail legs *c* and the axle *a* by the arrangement of one of the members of the said suspension on each of the trail legs, a corresponding complementary member being carried by the axle, the said arrangement being such that the suspension is rendered automatically operative by the trail legs being brought together for travelling and automatically inoperative by the said trail legs being spread apart for bringing the gun into the battery position.

In the constructional example shown in Figures 1 to 4, the axle *a*, in the vicinity of each of its ends, carries a resilient buffer *d*. A supporting member, such as a finger or nose *e*, projects laterally from the corresponding trail leg *c* and cooperates with said buffer *d* during travelling.

In order to facilitate this arrangement, it is possible, as shown in Figures 1 and 2, to employ a trail-carrying rocking beam bent into stirrup shape and oscillating about a pivot *b'* extended forwardly of the axle, the body of the said rocking beam being thus disposed in front of the axle,

while the arms b^2 of the stirrup, which surrounds the axle by an opening b^3 , carry in their ends situated to the rear of the axle the pivots c' of the corresponding trail legs. In this case, the trail legs may each terminate in a fork c^2-c^2 , the supporting member e for the resilient suspension being in the form of a lateral projection on the said fork (Figure 4).

A plug pin f' with corresponding bearings f formed on the arms c^2 of the forks is provided for locking the trail legs on the rocking beam in the battery position.

As shown clearly in Figure 1, in the firing position when the trail legs c have been moved apart, the supporting members e will have been automatically moved away from the corresponding resilient buffers d carried by the axle. The said members are brought automatically vertically above the buffers d when the trail legs are brought together for travelling; for example, for coupling to a gun limber.

The resilient buffer which forms one of the members of the suspension, may, as shown in Figure 3, advantageously be constituted by a cylinder d , carried by a stud d' (Figures 1 and 2) which is fitted in a corresponding seat provided in the axle a and which is secured by means of a nut d^2 . In this cylinder d , a spring d^3 may be compressed more or less between two supports d^4, d^5 . Fitted in the head d^6 of a rod d^{10} may be a mushroom head d^7 , suitably shaped to form an inclined plane for facilitating the sliding into engagement therewith of the supporting member e , a washer d^8 of resilient or compressible material being interposed between the rod head d^6 and the said mushroom head d^7 . Rod d^{10} is slidably mounted in cylinder d with the underside of rod head d^6 in position to engage the upper end of and to be resisted by the upward thrust of spring d^3 when the rod is depressed by its associated supporting member e .

Preferably, the resilient suspension just described is combined with an additional permanent resilient suspension, constituted by a resilient bush, interposed between the axle a and the pivot b' of the trail-carrying rocking beam. In the example shown, this additional suspension comprises a ring g of rubber or other like material which is provided with flat lateral portions g' for preventing its rotation, and which is set in a seat provided in the axle a . Arranged in a recess in the said resilient ring is a metallic ring g^2 , the thickness of which is preferably greater in the upper part, in order to prevent its rotation in the rubber ring. As shown in Figure 2, this metallic ring g^2 forms a bearing for the pivot b' of the rocking beam b .

If this additional suspension, which enables some of the shocks to which the wheels are subjected during travelling to be absorbed, is used, it is necessary to provide a mutual guide between the unit, formed by the trail-carrying rocking beam and trail legs, and the axle, in order to prevent any relative transverse displacement between the trail-carrying rocking beam and the set of wheels. In the example shown, this guide is provided by a profiled projection c^3 which is formed on each of the trail legs and which in the travelling position, bears against the wall of the corresponding buffer cylinder d (Figures 1 and 3).

In the drawings in the example just described, there is shown, particularly in Figure 5, a known type of top carriage h in which is trunnioned the oscillating mass (cradle i and gun j), the said

top carriage pivoting in a known manner about a vertical pivot k in the trail-carrying rocking beam b to permit training of the gun.

In the embodiment of the invention which has just been described it is necessary to extend the trail legs forwardly of the axle, and to offset this extension of the trail legs angularly at a point where, in the case of certain types of gun carriages, obstruction may be caused by the presence of other members, such as the wheel brake (a typical wheel brake being shown diagrammatically in Figure 1 merely by way of example). If it is desired to avoid this offset construction in such gun carriages, the modification shown in Figures 6 to 9 may be employed.

In this second embodiment of the invention, the rocking beam b , as shown in the drawings, is mounted in a recess in the axle a . It is stirrup-shaped, as in the preceding example, and the trail legs c are pivoted to the said rocking beam by 20 their forked ends, the forks of which engage above and below the arms of the rocking beam. In this construction, however, the trail legs are not extended forwardly of the axle, and the buffers d are mounted directly in the axle body, thus 25 obviating for the greater part any projection to the front of the axle.

Figure 10 shows still another modification of the invention, in which the stirrup-shaped rocking beam is disposed wholly rearwardly of the 30 axle a , the buffers d being mounted in projections provided on, and forwardly of, the axle a .

In the embodiment of Figures 11 and 12, the rocking beam b is disposed forwardly of the axle as in the example of Figures 1 to 4. In this construction, the rocking beam is not stirrup-shaped but, instead, the forked heads of the trail legs c are inclined inwardly towards the trail body, pass through the axle and carry rearwardly of the said axle the supporting members e for the resilient suspension, the complementary supporting members being constituted, as in the previous examples, by resilient buffers d carried by the axle, these members d and e being disposed between the longitudinal axial plane of the gun carriage 45 and the trail legs, instead of being disposed between the trail legs and the wheels, as in the previous examples.

Figures 13 and 14 show another embodiment in which the supporting member e is carried by the axle a , whereas the resilient buffer d is carried by the trail head. A simple consideration of the figures will clearly show that, as in the previous examples, by bringing the trail legs together, the resilient suspension is rendered operative by the buffer d coming vertically above the supporting members e (Figure 13), whereas, by moving the trail legs apart for bringing the gun-carriage into the battery position, the buffers d are moved away from the supporting members e (Figure 14).

As shown in Figures 13 and 14, a boss a' , on which bears a profiled projection c^3 of the trail head, may be provided on the axle as a mutual guide for the trail legs and the axle, with a view to employing the resilient bush additional permanent resilient suspension described in connection with Figures 1 to 4.

What is claimed is:

1. In a gun carriage of the split-trail type including an axle, a rocking beam mounted for pivotal movement relative to said axle about a longitudinal axis perpendicular to the axle and to said beam and a pair of trail legs secured to said rock- 75

ing beam for movement about substantially vertical axes, a resilient suspension for said rocking beam and trail legs comprising a pair of resilient buffer members and a pair of complementary buffer engaging members, one of said pairs of members being carried by said axle on opposite sides of a vertical plane through said longitudinal axis and the other pair being carried one by each of said trail legs, said members being so constructed and arranged that when the trail legs are spread in battery position said members are out of engagement with one another but when said trail legs are moved together in travelling position said members are automatically brought into engagement and provide a resilient suspension for the rocking beam and trail legs with respect to said axle.

2. In a gun carriage of the split-trail type including an axle, a rocking beam mounted for pivotal movement relative to said axle about a longitudinal axis perpendicular to the axle and to said beam and a pair of trail legs secured to said rocking beam for movement about substantially vertical axes, a resilient suspension for said rocking beam and trail legs comprising a pair of resilient buffer members carried by said axle adjacent the ends thereof, and a pair of complementary buffer engaging members carried one by each of said trail legs, said members being so constructed and arranged that when the trail legs are spread in battery position said members are out of engagement with one another but when said trail legs are moved together in travelling position said members are automatically brought into engagement and provide a resilient suspension for the rocking beam and trail legs with respect to said axle.

3. In a gun carriage of the split-trail type including an axle, a rocking beam mounted for pivotal movement relative to said axle about a longitudinal axis perpendicular to the axle and to said beam and a pair of trail legs secured to said rocking beam for movement about substantially vertical axes, a resilient suspension for said rocking beam and trail legs comprising a pair of resilient buffer members carried one by each of said trail legs, and a pair of complementary buffer engaging members carried by said axle on opposite sides of a vertical plane through said longitudinal axis, said members being so constructed and arranged that when the trail legs are spread in battery position said members are out of engagement with one another but when said trail legs are moved together in travelling position said members are automatically brought into engagement and provide a resilient suspension for the rocking beam and trail legs with respect to said axle.

4. A resilient suspension according to claim 1 wherein each of the resilient buffer members comprises a cylinder, a compression spring within said cylinder, supports carried by said cylinder for each end of said spring to limit the extension thereof, and a rod slidably mounted within said cylinder and having an enlarged head adapted to engage one end of said spring, said head having an outer surface which is so shaped as to facilitate the engagement therewith of said buffer engaging member when the trail legs are moved to travelling position.

5. A resilient suspension according to claim 1 wherein each of the resilient buffer members comprises a cylinder, a compression spring within said cylinder, supports carried by said cylinder for each end of said spring to limit the extension thereof, and a rod slidably mounted within said

cylinder and having an enlarged head adapted to engage one end of said spring, said head having a mushroom-shaped outer surface the profile of which forms an inclined plane for facilitating the engagement therewith of said buffer engaging member when the trail legs are moved to travelling position.

6. A resilient suspension according to claim 2 wherein each of the resilient buffer members comprises a cylinder, a stud carried by said cylinder and adapted to be removably secured to said axle, a compression spring within said cylinder, supports carried by said cylinder for each end of said spring to limit the extension thereof, and a rod slidably mounted within said cylinder and having an enlarged head adapted to engage one end of said spring, said head having an outer surface which is so shaped as to facilitate the engagement therewith of said buffer engaging member when the trail legs are moved to travelling position.

7. A gun carriage of the split-trail type comprising an axle, a rocking beam mounted for pivotal movement relatively to said axle about a longitudinal axis perpendicular to the axle and to said beam, an oscillating gun and cradle carried by said beam and mounted for pivotal movement relatively thereto about a substantially vertical axis, a pair of trail legs secured to said rocking beam for movement about substantially vertical axes, a pair of resilient buffer members, and a pair of complementary buffer engaging members, one of said pairs of members being carried by said axle on opposite sides of a vertical plane through said longitudinal axis and the other pair being carried one by each of said trail legs, said members being so constructed and arranged that when the trail legs are spread in battery position said members are out of engagement with one another but when said trail legs are moved together in travelling position said members are automatically brought into engagement and provide a resilient suspension for the rocking beam, oscillating gun and cradle and trail legs with respect to said axle.

8. A gun carriage of the split-trail type comprising an axle, a rocking beam mounted for pivotal movement relatively to said axle about a longitudinal axis perpendicular to the axle and to said beam, an oscillating gun and cradle carried by said beam and mounted for pivotal movement relatively thereto about a substantially vertical axis, a pair of trail legs pivotally connected to the ends of said beam for movement about substantially vertical axes, each of said trail legs having a portion extending forward of its pivot point, a pair of resilient buffer members carried by said axle adjacent the ends thereof, and a pair of complementary buffer engaging members carried one by each of said forwardly extending portions of said trail legs, said members being so constructed and arranged that when the trail legs are spread in battery position said members are out of engagement with one another but when said trail legs are moved together in travelling position said members are automatically brought into engagement and provide a resilient suspension for the rocking beam, oscillating gun and cradle and trail legs with respect to said axle.

9. A gun carriage of the split-trail type comprising an axle, a rocking beam mounted forwardly of said axle for pivotal movement relatively thereto about a longitudinal axis perpendicular to the axle and to said beam, the ends of said beam extending rearwardly of said axle, an oscillating gun and cradle carried by said beam

and mounted for pivotal movement relatively thereto about a substantially vertical axis, a pair of trail legs pivotally connected to the ends of said beam for movement about substantially vertical axes, a pair of resilient buffer members carried by said axle adjacent the ends thereof and a pair of complementary buffer engaging members carried one by each of said trail legs, said members being so constructed and arranged that when the trail legs are spread in battery position said members are out of engagement with one another but when said trail legs are moved together in travelling position said members are automatically brought into engagement and provide a resilient suspension for the rocking beam, oscillating gun and cradle and trail legs with respect to said axle.

10. A gun carriage of the split-trail type comprising an axle, a rocking beam mounted forwardly of said axle for pivotal movement relatively thereto about a longitudinal axis perpendicular to the axle and to said beam, the ends of said beam being stirrup-shaped and extending rearwardly of and around said axle, an oscillating gun and cradle carried by said beam and mounted for pivotal movement relatively thereto about a substantially vertical axis, a pair of trail legs pivotally connected to the stirrup-shaped ends of said beam for movement about substantially vertical axes, each of said trail legs having a portion extending forwardly of its pivot point, a pair of resilient buffer members carried by said axle adjacent the ends thereof, and a pair of complementary buffer engaging members carried 30 one by each of said forwardly extending portions of said trail legs, said members being so constructed and arranged that when the trail legs are spread in battery position said members are out of engagement with one another but when 40 said trail legs are moved together in travelling position said members are automatically brought into engagement and provide a resilient suspension for the rocking beam, oscillating gun and cradle and trail legs with respect to said axle.

45. 11. A gun carriage of the split-trail type comprising an axle, a rocking beam mounted forwardly of said axle for pivotal movement relatively thereto about a longitudinal axis perpendicular to the axle and to said beam, the ends of 50 said beam being stirrup-shaped and extending rearwardly of and around said axle, the walls of the openings in said stirrup-shaped ends through which the axle passes constituting means for limiting the extent of relative transverse oscillation 55 between said beam and axle about said longitudinal axis, an oscillating gun and cradle carried by said beam and mounted for pivotal movement relatively thereto about a substantially vertical axis, a pair of trail legs pivotally connected to the stirrup-shaped ends of said beam for movement about substantially vertical axes, a pair of resilient buffer members carried by said axle adjacent the ends thereof, and a pair of complementary buffer engaging members carried one 60 by each of said trail legs, said members being so constructed and arranged that when the trail legs are spread in battery position said members are out of engagement with one another but when said trail legs are moved together in travelling position said members are automatically brought into engagement and provide a resilient suspension for the rocking beam, oscillating gun 65

and cradle and trail legs with respect to said axle.

12. A gun carriage of the split-trail type comprising an axle, a rocking beam mounted forwardly of said axle for pivotal movement relatively thereto about a longitudinal axis perpendicular to the axle and to said beam, the ends of said beam extending rearwardly through openings in said axle, an oscillating gun and cradle carried by said beam and mounted for pivotal movement relatively thereto about a substantially vertical axis, a pair of trail legs secured to the ends of said rocking beam for movement about substantially vertical axes, a pair of resilient buffer members carried by said axle adjacent the ends thereof, and a pair of complementary buffer engaging members carried one by each of said trail legs, said members being so constructed and arranged that when the trail legs are spread in battery position said members are out of engagement with one another but when said trail legs are moved together in travelling position said members are automatically brought into engagement and provide a resilient suspension for the rocking beam, oscillating gun and cradle and trail legs with respect to said axle.

13. A gun carriage according to claim 7 wherein the pivotal connection between said rocking beam and axle comprises a pivot pin carried by said beam, a bearing seat for said pin formed in said axle, a metallic bearing ring engaging said pivot pin, and a resilient bush of compressible material interposed between said bearing seat and said ring.

14. A gun carriage according to claim 7 wherein the pivotal connection between said rocking beam and axle comprises a pivot pin carried by said beam, a bearing seat for said pin formed in said axle, a metallic bearing ring engaging said pivot pin, and a resilient bush of compressible material interposed between said bearing seat and said ring, said bearing seat and resilient bush having correspondingly flattened portions to prevent rotation of said bush relative to said seat, and said bearing ring being thicker at one portion of its periphery than elsewhere to prevent rotation thereof within the resilient bush.

15. A gun carriage according to claim 7 wherein the pivotal connection between said rocking beam and axle comprises a pivot pin carried by said beam, a bearing seat for said pin formed in said axle, a metallic bearing ring engaging said pivot pin and a resilient bush of compressible material interposed between said bearing seat and said ring, and which includes means for preventing relative movement between said beam and axle transversely to the axis of said pivot pin.

16. A gun carriage according to claim 7 wherein the pivotal connection between said rocking beam and axle comprises a pivot pin carried by said beam, a bearing seat for said pin formed in said axle, a metallic bearing ring engaging said pivot pin and a resilient bush of compressible material interposed between said bearing seat and said ring, and which includes cooperating surfaces carried by said axle and said trail legs which are automatically brought into engagement with one another when said trail legs are moved to travelling position for preventing relative movement between said rocking beam and axle transversely to the axis of said pivot pin.

NICOLAS EMILIEU METHLIN.
